UNITED STATES PATENT OFFICE.

FREDERICK U. CONARD, OF BRIDGEPORT, CONNECTICUT, ASSIGNOR TO UNDERWOOD TYPEWRITER COMPANY, OF NEW YORK, N. Y., A CORPORATION OF DELAWARE.

TYPEWRITING MACHINE.

Application filed August 20, 1925. Serial No. 51,319.

This invention relates to sound-deadening casings for typewriting machines, in which the machine is completely enclosed within the casing except for the keyboard, which 5 protrudes through the front wall to the outside thereof.

According to this invention, the typewriter is placed in a casing comprising a body-part and a cover therefor. The body- 10 part includes a bottom wall or sole forming an integral part of rear, side and front walls, the latter being provided with an opening through which the keyboard of the machine extends to the exterior, to render the machine 15 operable without displacing the cover, which, when in its effective or closed position, completely prevents the emission of sounds and confines them within the casing.

One of the features of this invention relates 20 to improved means for returning the carriage. Heretofore it has been customary to provide slots in front of the casing adjacent the carriage, through which slot the carriage-control levers of the machine extended to the outside of the casing to render the carriage operable. One of the objections 25 of said slots is that the machine must be equipped with special carriage-control levers which is objectionable because it increases the manufacturing cost of the machine. Another objection is that some of 30 the sound produced when operating the machine leaks therethrough, and, of course, lowers the sound-deadening efficiency of the casing. In this invention there is provided a drum around which a cord is wound by means of a handle protruding to the outside of the casing through the front wall thereof. Said handle is operatively connected to 35 the drum by means of gearing, or otherwise, and the cord on the drum is operatively connected to the line-space lever of the carriage. Upon operating the lever in front of the casing, the drum is rotated to wind the cord 40 therearound, thus drawing on the cord and operating the line-space lever, thereby line-spacing the platen and concomitantly returning the carriage.

Another feature of this invention relates 45 to means whereby the carriage may be positioned to correspond to indications in the

regular scale of the machine which may be seen through a glass-covered opening at the top of the casing. To this end, there is provided a cord wound around the periphery 55 of a drum operatively connected to a lever arm in front of the casing. One end of the cord is fastened to the carriage-release lever of the machine in a manner to afford the releasing of the carriage when the drum is 60 rotated to pull the carriage in letter-space direction. The other end of the cord is secured to the frame of the carriage and is led to the drum by means of cooperating pulleys. Since the carriage is at all positions 65 released to move in counter-letter-space direction, the drum may be rotated to pull on the carriage directly in returning direction. By releasing the lever arm in front of the casing, the carriage-release lever is 70 automatically restored to its normal position, thereby holding the carriage in place ready for typing.

Other features and advantages will hereinafter appear.

In the accompanying drawings,

Figure 1 is a cross-sectional plan view of a sound-deadening casing having an Underwood standard typewriting machine applied thereto, and showing the carriage-control 80 mechanism which forms the subject of this invention.

Figure 2 is a front cross-sectional view in elevation, showing the carriage-return mechanism.

Figure 3 is a side cross-sectional view in elevation, showing the carriage-return mechanism.

Figure 4 is a diagrammatic front view in elevation of the carriage-return mechanism.

Figure 5 is a front view in elevation of the sound-deadening casing.

Figure 6 is a front cross-sectional view in elevation, showing the carriage-release mechanism.

Figure 7 is a transverse cross-sectional view of the casing, showing the carriage-return mechanism applied thereto.

Figure 8 is a fragmentary front view of the carriage, showing the anchoring points 100 of the cord controlling the carriage-release lever.

According to this invention, an Underwood typewriting machine is secured to a base 10 and is completely enclosed to confine the noise arising from the operation thereof.

5 The casing comprises a body-part and a cover 11 rockably mounted on a hinge 12 fast to the body-part at the rear thereof. The body-part, which is herein shown in its simplest form comprises a rear wall 13, side 13 walls 14 and a front wall 15 provided with an opening 16 through which protrudes a keyboard-extension 17 having banks of keys 18. The body-part is secured to the base 10 in the regular way by means of screws, not 15 shown, and may be lined with a layer of felt 19 for the purpose of further deadening the sounds arising from the operation of the machine. The cover 11 comprises side and rear walls forming an integral part of a 20 curvate top 20 in which there is provided a glass-sealed opening 21 to render the printing point of the machine visible. Said cover may also be lined with a layer of felt 22 to increase further the sound-deadening efficiency of the casing.

In order that the carriage, which is generally indicated by the numeral 23, may be returned to its starting position at the end of each line of typing, and in order that 30 the work-sheet may be automatically line-spaced while returning the carriage without necessitating the opening of the cover, there is provided mechanism controlled by a lever 24 fast to a shaft 25 journaled in a bushing 26 fast to the front wall of the casing and at the left side thereof. Since the Underwood machine is normally equipped with a left-hand carriage-return lever, it has been found advantageous to place the lever 24 at 40 the left of the casing, thus making it handier for the operative to return the carriage. The shaft 25 is operatively connected to a second shaft 27 by means of a sector 28 fast to the shaft 25 and meshing with a pinion 29 secured to the shaft 27, which carries also fast thereto, a drum 30 around which a cord 31 is wound when the drum is rotated by the action of depressing the lever 24. The free end of the cord 31 is passed around 50 pulleys 32 and 33 which are secured to the base 10, and is led over a third pulley 34 to guide the cord in line with a line-space lever 35 on the carriage 23, to which it is secured in a manner shown in Figure 1. In order to take up the slack of the cord, 55 there may be provided a spring, not shown, in a housing 36, said spring being effective to rotate the shaft 27 and to wind the cord around the drum when the carriage is manually returned.

One of the features of this invention relates to means to position the carriage or to return the carriage without line-spacing the work-sheet. To this end, there is pro-

vided mechanism comprising a handle 37 fast to a shaft 38 journaled in a bearing 39 secured to the front wall of the casing. Upon said shaft 38 there is provided a sector 40 which meshes with a pinion 41 fast to a shaft 42 journaled in the front and rear walls of the casing, the bearings being respectively numbered 43 and 44. Upon the shaft 42 there are provided two drums 45 each having a cord wound therearound, the cords being respectively numbered 46 and 47. The free end of the cord 46 is passed over a pulley 48 and is secured to a pin 49 fast to the carriage of the machine, while the end of the cord 47 is led under pulleys 50 and 51 and up over a pulley 52 to be secured through a hole 53 in the carriage to a carriage-release lever 54. According to the method of operating this mechanism, the handle 37 is swung either to the right to draw on the carriage by means of the cord 46, or to the left to pull on the cord 47, thereby releasing the carriage, thus permitting the carriage to be moved to the left. Since the carriage is released at all times in return direction it may be moved to the right by simply pulling on the cord 46. However, in order to pull it to the left, that is to say, to permit the carriage to be moved by the regular letter-space spring, the operating connection between the carriage and the escapement mechanism is severed by pulling on the cord 47 which actuates the lever 54.

Variations may be resorted to within the scope of the invention, and portions of the improvements may be used without others.

Having thus described my invention, I claim:

1. The combination with a sound-deadening casing for a typewriting machine, said machine having a revoluble platen, a letter-feeding carriage therefor, and escapement-mechanism for said carriage, of means associated with said carriage for releasing the same from the escapement-mechanism to permit it to move to the left, or for moving it to the right, said means being controlled by a single pivoted lever operable from the outside of the casing, said lever, upon rocking the same constantly in one direction, actuating said means so as to release the carriage from the escapement-mechanism, and, upon rocking the same constantly in the reverse direction, actuating said means to move said carriage to the right.

2. The combination with a sound-deadening casing for a typewriting machine having a revoluble platen, a carriage therefor, a line-spacing lever and a carriage-release lever, of means controlled by a crank in front of the casing and effective to simultaneously line-space the platen and return the carriage, said means including a drum operatively connected to said crank, a cord wound

therearound, means for guiding the cord to the carriage, and means for securing one end of the cord to the line-space lever whereby the carriage will be concomitantly returned when operating the crank in front of the casing.

3. The combination with a sound-deadening casing for a typewriting machine having a revolute platen, a carriage therefor, a line-spacing lever and a carriage-release lever, of means controlled by a lever in front of the casing and effective to simultaneously line-space the platen and return the carriage, and means operatively connecting the carriage-release lever to a crank outside of the casing and in front thereof, whereby the carriage may be released and moved in either letter-space or returning direction.

4. The combination with a sound-deadening casing for a typewriting machine having a revolute platen, a carriage therefor, a line-spacing lever and a carriage-release lever, of means controlled by a lever in front of the casing and effective to simultaneously line-space the platen and return the carriage, and means operatively connecting the carriage-release lever to a crank outside of the casing and in front thereof, whereby the carriage may be released and moved in either letter-space or returning direction, said last-mentioned means including mechanism for operatively connecting the crank to a revolving shaft upon which there are mounted two drums each having a cord wound therearound, one of the cords being secured to the line-space lever while the other is fastened to the carriage in such a manner as to afford the movement of the carriage in the direction toward which the cord of either drum is pulling.

5. The combination with a sound-deadening casing for a typewriting machine having a revolute platen, a carriage therefor, a line-spacing lever and a carriage-release lever, of means controlled by a lever in front of the casing and effective to simultaneously line-space the platen and return the carriage, said last-mentioned lever being positioned at the left side of the front wall of the casing to correspond with the normal operation of the machine.

6. The combination with a sound-deadening casing for a typewriting machine having a revolute platen, a carriage therefor, a line-spacing lever and a carriage-release lever, of means controlled by a crank in front of the casing and effective to simultaneously line-space the platen and return the carriage, said means including a left-handed mechanism to rotate a drum by the operation of the crank, a cord wound around the drum and pulleys to guide the cord to be led to the right over the bottom wall of the casing and then upwardly over another

pulley in line with the line-spacing lever to which the end of the cord is secured.

7. The combination with a typewriting machine having a revolute platen, a carriage therefor, means for letter-spacing said carriage, a carriage-release lever whereby the carriage may be disconnected from the letter-spacing means, and a line-spacing lever operatively connected to the platen, of a sound-deadening casing completely enclosing the machine except for the keyboard extension thereof, and means controlled by a handle to return the carriage, said handle being rockably mounted in the front wall of the casing, at the left-hand side thereof.

8. The combination with a typewriting machine having a revolute platen, a carriage therefor, means for letter-spacing said carriage, a carriage-release lever whereby the carriage may be disconnected from the letter-spacing means, and a line-spacing lever operatively connected to the platen, of a sound-deadening casing completely enclosing the machine except for the keyboard extension thereof, means controlled by a handle to return the carriage, said handle being rockably mounted in the front wall of the casing at the left-hand side thereof, and means controlled by a handle in the front wall of the casing and at the right-hand side thereof, for positioning the carriage.

9. The combination with a typewriting machine having a revolute platen, a carriage therefor, means for letter-spacing said carriage, a carriage-release lever whereby the carriage may be disconnected from the letter-spacing means, and a line-spacing lever operatively connected to the platen, of a sound-deadening casing completely enclosing the machine except for the keyboard-extension thereof, means controlled by a handle to return the carriage, said handle being rockably mounted in the front wall of the casing at the left-hand side thereof, said last-mentioned means including a drum operatively connected to the handle and a cord wound around the drum, the cord having one end fast to the drum and the other end fast to the line-spacing lever on the carriage.

10. The combination with a typewriting machine having a revolute platen, a carriage therefor, means for letter-spacing said carriage, a carriage-release lever whereby the carriage may be disconnected from the letter-spacing means, and a line-spacing lever operatively connected to the platen, of a sound-deadening casing completely enclosing the machine except for the keyboard-extension thereof, means controlled by a handle to return the carriage, said handle being rockably mounted in the front wall of the casing at the left-hand side thereof, and means controlled by a handle in the

front wall of the casing and at the right-hand side thereof, for positioning the carriage, said last-mentioned means including a pair of drums operatively connected to the last-mentioned handle in a manner to afford the rotation of the drums when the handle is operated, a pair of cords each wound around one of the drums, and means for guiding the cords within the casing, one of the cords being secured to the carriage whereby the same may be moved in returning direction, and the other cord being secured to the carriage-release lever in a manner to afford the release of the carriage when the drum is rotated in a direction to wind the cord and to draw on the carriage-release lever.

11. The combination with a typewriting machine having a traveling carriage, an escapement mechanism therefor, a platen revolvably mounted on said carriage, a line-spacing lever on said carriage, and a carriage-release lever, of a sound-deadening casing completely enclosing the machine except for an opening in front of the casing through which the keyboard of the machine protrudes to the exterior of the casing, and means for operatively connecting the line-spacing lever to a crank journaled in the front wall of said casing in a manner to afford the return of the carriage and the line-spacing of the platen when the crank is rotated.

12. The combination with a typewriting machine having a traveling carriage, an escapement mechanism therefor, a platen revolvably mounted on said carriage, a line-spacing lever on said carriage, and a carriage-release lever, of a sound-deadening casing completely enclosing the machine except for an opening in front of the casing through which the keyboard of the machine protrudes to the exterior of the casing, and means for operatively connecting the line-spacing lever to a crank journaled in the front wall of said casing in a manner to afford the return of the carriage and the line-spacing of the platen when the crank is rotated, said means including a drum operatively connected to said crank and a cord wound around said drum and having the free end of the cord fast to the line-spacing lever.

13. The combination with a typewriting machine having a traveling carriage, an escapement mechanism therefor, a platen revolvably mounted on said carriage, a line-spacing lever on said carriage, and a carriage-release lever, of a sound-deadening casing completely enclosing the machine except for an opening in front of the casing through which the keyboard of the machine protrudes to the exterior of the casing, and means for operatively connecting the car-

riage-release lever to a crank journaled in the front wall of the casing in a manner to afford the release of the carriage when the crank is operated in one direction, and to lock the carriage upon reversing the direction of swing of said crank.

14. The combination with a typewriting machine having a traveling carriage, an escapement mechanism therefor, a platen revolvably mounted on said carriage, a line-spacing lever on said carriage, and a carriage-release lever, of a sound-deadening casing completely enclosing the machine except for an opening in front of the casing through which the keyboard of the machine protrudes to the exterior of the casing, and means for operatively connecting the carriage-release lever to a crank journaled in the front wall of the casing in a manner to afford the release of the carriage when the crank is operated in one direction, and to lock the carriage upon reversing the direction of swing of said crank, said means including a pair of drums operatively connected to the crank, each drum having a cord wound therearound, one of the cords being operatively connected to the carriage-release lever, and the other cord being operatively connected to the frame of the carriage.

15. The combination with a sound-deadening casing for a typewriting machine having a revoluble platen, a letter-feeding carriage therefor, and a carriage-release lever, of a winding drum within the casing, a handle on the outside of the casing, operating connections between the handle and the drum for rotating the latter in either direction, and a pair of cords, one end of each of said cords being attached to the drum in such manner that when the drum is turned in one direction, one of the cords is wound on said drum while the other one is unwound therefrom, the free end of one of said cords being connected directly to the carriage whereby operation of said handle in one direction moves the carriage to the right, the free end of the other cord being associated with the carriage-release lever and effective when the handle is moved in the other direction to cause the release of said lever and the travel of the carriage to the left.

16. The combination with a sound-deadening casing for a typewriting machine, said machine having a platen, a carriage therefor, escapement-mechanism for said carriage and a carriage-release-lever, of means connected to said carriage-release-lever to actuate the same to release the carriage from said escapement-mechanism to permit the carriage to move to the left, means connected to said carriage and operable to move the same to the right, and a single control operable from the outside of said casing selectively to actuate either of said means to

cause motion of said carriage either to the left or to the right.

17. The combination with a sound-deadening casing for a typewriting machine, said machine having a revoluble platen, a carriage therefor, and a carriage-return-lever, of a crank having a shaft journaled in the front wall of said casing at the left side thereof and operable from the exterior of the casing, a drum mounted in the interior

of the casing and operatively connected to said crank-shaft, a cable wound upon said drum, and means for guiding said cable to the right side of said casing and to the level of said carriage-return-lever, the free end ¹⁵ of said cable being attached to said lever to actuate the same upon rotation of said drum by said crank.

FREDERICK U. CONARD.
